Certificate of Correction.

It is hereby certified that the name of the assignee in Design Letters Patent No. 68,232, granted September 22, 1925, upon the application of Michael B. Bowen, of Decatur, Illinois, for an improvement in "A Portable Desk Lamp," was erroneously written and printed as "Fraries Manufacturing Company," whereas said name should have been written and printed as Fraries Manufacturing Company, as shown by the records of assignments in this office; and that the said Letters Patent should be read with this correction therein that the same may conform to the record of the case in the Patent Office.

Signed and sealed this 27th day of October, A. D. 1925.

KARL FENNING,
Acting Commissioner of Patents.

UNITED STATES PATENT OFFICE.

MICHAEL B. BOWEN, OF DECATUR, ILLINOIS, ASSIGNOR TO FRARIES MANUFACTURING COMPANY, OF DECATUR, ILLINOIS, A CORPORATION OF ILLINOIS.

DESIGN FOR A PORTABLE DESK LAMP.

Application filed March 21, 1922. Serial No. 1,322. Term of patent 7 years.

To all whom it may concern:

Be it known that I, MICHAEL B. BOWEN, a citizen of the United States, and residing at Decatur, in the county of Macon and State of Illinois, have invented a new, original, and ornamental Design for Portable Desk Lamp, of which the following is a specification, reference being had to the accompanying drawing, forming part thereof.

Fig. 1 is a front view of my lamp, partially in perspective; Fig. 2 is a three-quarter rear view, also partially in perspective, of my improved design for portable desk lamp.

I claim—

The ornamental design for a portable desk lamp, as shown.
